(57) **CLAIM**

The ornamental design for a shoe as shown and described.

DESCRIPTION

FIG. 1 is a front perspective view of a shoe showing my new design;

FIG. 2 is a side view thereof; and,

FIG. 3 is a rear perspective view thereof.

The contrast in stipple shading density between the three regions represents a contrast in appearance only and does not represent any particular color, material, texture, or finish. The six broken line circles within the shaded area represent eyelets that form no part of the claimed design. The broken line immediately adjacent to the rear of the shaded area defines the bounds of the claimed design and forms no part thereof. The broken lines depicting the remainder of the shoe form no part of the claimed design.

1 Claim, 3 Drawing Sheets
